[57] CLAIM

The ornamental design for a combination hot or cold beverage/can holder, as shown and described.

DESCRIPTION

FIG. 1 is a perspective view of a combination hot or cold beverage/can holder showing my new design;

FIG. 2 is a side elevation view thereof;

FIG. 3 is a top plan view thereof;

FIG. 4 is a bottom plan view thereof;

FIG. 5 is a perspective view of an alternate embodiment of FIG. 1;

FIG. 6 is a side elevation view of an alternate embodiment of FIG. 1;

FIG. 7 is a top plan view of FIG. 5; and,

FIG. 8 is a bottom plan view of FIG. 5.

The broken lines showing the cans are for illustrative purposes only and form no part of the claimed design.
